UNITED STATES PATENT OFFICE.

WILLIAM THOMAS EADES AND EDMUND ALLDAY, OF SMALL HEATH, NEAR BIRMINGHAM, ENGLAND.

HOIST.

SPECIFICATION forming part of Letters Patent No. 657,815, dated September 11, 1900.

Application filed May 3, 1900. Serial No. 15,394. (No model.)

To all whom it may concern:

Be it known that we, WILLIAM THOMAS EADES and EDMUND ALLDAY, manufacturers, subjects of the Queen of Great Britain, residing at Sydenham road, Small Heath, near the city of Birmingham, England, have invented certain new and useful Improvements in Hoists, of which the following is a specification.

- 10 This invention relates to hoists or lifts principally for use in warehouses and the like, and has for its object to construct a lift or hoist adapted to raise various loads at different speeds and provided with automatic 15 lowering-gear and also with an automatic brake by which the hoist is made to efficiently sustain its load at all speeds of lifting.
- Figure 1 of the accompanying drawings represents a side elevation of a self-sustaining warehouse-hoist designed for lifting varied loads and having an automatic brake in accordance with one form of our invention. This apparatus is designed to lift at three different speeds, (or two speeds beyond the 25 ordinary speed,) according to the weight of the load to be raised—viz., a slow speed for heavy loads, an intermediate speed (about four times faster than the slow speed) for raising moderate loads, and a high speed for dealing with light loads, which are lifted at a rate about eight times faster than is obtained with the slow-speed gear. This view clearly shows the arrangement of the brake, the automatic means for sustaining the load, and the means 30 for disengaging the brake to permit of automatic running down or lowering. Fig. 2 represents an end elevation of the said hoist; and Fig. 3 represents a transverse vertical section of the same upon the dotted lines *x*, Fig. 1.
- 40 The same letters of reference indicate corresponding parts in the figures.

According to this form of the invention the axle or shaft *a* of the hoist or lift is supported at one end *a'* in an open-topped bearing *b'*, carried by the fixed framing *b* of the hoist, while the other end *a²* has mounted loosely upon it a brake-wheel *c*, having a central boss *c'*, whose sleeved extension *c²* lies within an open-topped bearing *b²*, located on the opposite side of the fixed framing and constituting the second support for the said axle,

which is capable of rotating in either direction.

The periphery of the brake-drum normally has a bearing upon the inside of a friction 55 brake band or sling *d*, suspended at its ends from hanger-brackets *d'*, secured to the side framings, while this end *a²* of the shaft and the whole of the parts of the hoist carried by it are capable of being bodily lifted, so as to 60 take the periphery of the wheel out of contact with the braking-band by means of a long lever *e*, pivoted at *e'* to a separate bracket *e²* on the side framing, with its short arm coming underneath the extending end 65 part *a³* of the said shaft *e³*, while the longer arm is provided with a pull-cord *e⁴*. Loosely mounted upon a part of the shaft immediately inward of the brake-drum is a small-load wheel or slow-speed pulley *f* for heavy- 70 weight lifting, having arranged in conjunction with it a friction-clutch *g*, of the roller or other type, located within the recessed boss of the brake-wheel and adapted to act in such a manner as to permit of the rotation of the 75 said pulley in one direction, (for lifting,) but to render it incapable of rotation independent of the said brake-wheel in the other direction, so that when the pulley is clutched to the brake-wheel no running down of the 80 load being lifted by the slow-speed pulley can occur. Also loosely mounted upon the said shaft, but adjacent to the bearing *b'*, is another and larger pulley or intermediate-speed load-wheel *h* for quickly raising moderate loads provided with an integral or attached ratchet-wheel *i*, whose teeth are engaged by a pawl *i'*, carried on the framing and acting in such a manner as will permit of its pulley rotating for lifting in an opposite direction to that in which the smaller pulley turns for lifting, but will prevent it running down in the other direction by coupling it to the frame of the hoist. Either the one or the other of these lifting-pulleys, which 95 are confined against outward movement by stop-collars *f'* *h'*, keyed upon the shaft, is actuated by means of a hand-wheel *j*, operated by an endless rope or chain *j'* and traversed along the shaft, so as to come into operative frictional contact with the opposed face of either pulley by means of a screw or

helix α^5 on the said shaft and a screw-box j^2 , formed in the boss of the said hand-wheel, which is rotated and traversed either to the right or to the left, according to which pulley 5 is to be thrown into gear. An endless chain k passes over both the load-pulleys, with one of the loops k' thereof directed around the sheave of the hooked block k^2 .

Operation: Assuming that a moderate load 10 is required to be lifted at the intermediate speed, the endless rope passing around the hand-wheel is pulled at the side marked A in Figs. 1 and 2, and the said hand-wheel is thereby rotated in the direction indicated by 15 the full arrow in Fig. 1 and is at the same time made to traverse from right to left along its shaft through the medium of the helix α^5 and screw-box j^2 , and thus the said hand-wheel and the pulley h are clutched together 20 by the friction exerted between their opposed faces and are made to rotate in unison for raising the load, the said load being meanwhile sustained and the running back of the 25 said pulley h being prevented by the pawl i' engaging one of the teeth of the ratchet-wheel i , while the turning backward of the slow-speed pulley f is at the same time prevented by the pull exerted by the weight of the load upon the side of the chain marked o in 30 Fig. 1, actuating the clutch g , by which the said pulley f is coupled to the brake-wheel. Then as the rotation of the hand-wheel and pulley h in the aforesaid direction proceeds 35 the load is lifted by the chain passing over the said pulley at a speed four times faster than would be obtained by the small pulley or at any other desired speed, according to the diameter of the pulley over which the chain passes. Assuming now that the hoist 40 is required to lift a heavy weight at a slow speed, the endless rope is pulled at the side marked B in Fig. 1, so as to rotate the hand-wheel in the reverse direction, as indicated by the dotted arrow, when the hand-wheel is 45 disconnected from the large-load pulley and traversed by the screw on the shaft from left to right along the said shaft into operative connection with the small-load pulley f , which is thereby liberated from the brake-drum 50 and rotated with the hand-wheel for lifting the load which is sustained during the hoisting operation by the clutch g , preventing the running back of the small-load pulley, and by the pawl i' and ratchet-wheel i , holding 55 the large-load wheel stationary in opposition to the pull exerted upon it by the load and chain. The lifting of very light loads at the highest speed is effected by pulling the endless chain k at the side marked C in Fig. 1, 60 when the load is lifted at a speed proportionate to the diameter of the large-load wheel, which acts as a simple pulley, the running back of the load being prevented, as before, by the clutch g and brake-wheel and the pawl i' and ratchet i . To permit of the running 65 down of the load, the endless rope is pulled at B, if necessary, to disengage the hand-

wheel from the small-load pulley, and then the brake-release cord e^4 is pulled down, when the lever e is turned, and its short arm lifts 70 the adjacent end of the axle out of its bearing and takes the periphery of the brake-wheel more or less out of contact with the brake-band, when the brake-wheel and pulley rotate together around the axle and the 75 load is run down, but is under control, and the speed of running down is regulated by the attendant releasing the brake-cord e^4 when necessary and allowing the brake to act. The large pulley is kept stationary during 80 the descent of the load by the pawl-and-ratchet arrangement.

In some instances instead of obtaining the varying lifting speeds (according to the weights to be raised) by the employment 85 of load-pulleys of different diameters, as in the last-described arrangement, the same result may be obtained by differential-toothed gearing.

Having fully described our invention, what 90 we desire to claim and secure by Letters Patent is—

1. In a hoisting device, a shaft provided centrally with a helix, a hand-wheel mounted on the helix of the shaft, and a load-pulley 95 loosely mounted upon said shaft at each side of said wheel and adapted to be operated by frictional engagement with said wheel.

2. In a hoisting device, a shaft provided centrally with a helix, a hand-wheel mounted 100 on the helix of the shaft, a pair of load-pulleys suitably arranged upon said shaft and adapted to be operated by the frictional engagement therewith of the said wheel, a braking means suitably connected to one of said 105 pulleys, a ratchet-wheel carried by the other of said pulleys, and a pawl adapted to engage said ratchet-wheel.

3. In a hoisting device, a pair of load-pulleys of different diameters suitably mounted 110 upon a shaft, a hand-wheel adapted to frictionally engage said pulleys for operating the same, an endless cable for operating said hand-wheel in either direction, a brake-wheel resting upon a braking expedient, a friction-clutch adapted to be brought into engagement with one of said pulleys by means of said 115 brake-wheel, means for releasing said brake-wheel to permit of the running down of said pulley, a pawl-and-ratchet means connected to the other of said pulleys to prevent the running down thereof, and an endless chain 120 operating over the said pulleys, substantially as described.

4. In a hoisting device, a pair of load-pulleys of different diameters suitably mounted upon a shaft, a hand-wheel adapted to frictionally engage said pulleys for operating the same, a brake-wheel resting upon a braking expedient, a friction-clutch adapted to be 130 brought into engagement with one of said pulleys by means of said brake-wheel, means for releasing the said brake-wheel to permit the running down of said pulley which is

adapted to be connected thereto, and a pawl-and-ratchet means connected to the other of said pulleys and adapted to prevent the running down of the same.

5 5. In a hoisting device, a shaft journaled at each end in open-topped bearings, a load-pulley mounted thereon, operating means therefor, a brake-wheel resting upon a braking expedient, a clutch adapted to connect said brake-wheel and said pulley and a lever adapted to engage and elevate one end of said shaft for releasing said brake-wheel from the braking expedient.

10 6. In a hoisting device, a shaft provided centrally with a helix, a hand-wheel mounted upon the helix, a load-pulley carried by said

shaft at each side of the wheel and adapted to be operated by frictional engagement with said wheel, a pawl-and-ratchet means for preventing the running down of said pulleys, a 20 braking means for preventing the running down of the other of said pulleys, and a lever adapted to engage said shaft to release said braking means.

In testimony whereof we have hereunto set 25 our hands in presence of two subscribing witnesses.

WILLIAM THOMAS EADES.
EDMUND ALLDAY.
